UNITED STATES PATENT OFFICE

VICTOR A. FOISY, OF WORCESTER, MASSACHUSETTS, AND CARL J. LINDEGREN, OF PROVIDENCE, RHODE ISLAND, ASSIGNEES TO CROMPTON & KNOWLES LOOM WORKS, OF WORCESTER, MASSACHUSETTS, A CORPORATION OF MASSACHUSETTS

MULTICOLOR-WEFT-REPLENISHING MECHANISM FOR LOOMS

Application filed March 8, 1928. Serial No. 269,063.

This invention relates to improvements in multicolor weft replenishing mechanism and it is an important object of our present invention to provide means whereby bobbins of different lengths may be employed in the same magazine or replenishing mechanism.

Certain fabrics have incorporated into their construction both cotton and rayon, or worsted and rayon, and such fabrics are frequently made in mills which are provided with a silk or rayon department which is separate from the other departments, such as cotton or worsted. It is customary to weave silk with a somewhat smaller bobbin than is ordinarily employed for cotton and worsted, the bobbin for the finer yarn being as a rule shorter than the other bobbins, although they may be wound to substantially the same diameter. It is an important object of our present invention to adapt the ordinary so-called stationary magazine which is employed on fancy or box looms, so that certain of the vertical bobbin compartments will hold short bobbins while others will accommodate longer bobbins.

The usual form of multicolor weft replenishing mechanism has a so-called cradle or bobbin releasing device located at the bottom of each stack of reserve bobbins and there are vertically extending guides for the tips of the bobbins. It is a further object of our present invention to make the outside plate of the replenishing mechanism of several different sections, each section having one or more guides for the tips of the bobbins and also having provision for supporting the outer portions of the cradle or cradles which correspond to the guides. By this construction the parts which must be changed in order to accommodate a variation in the length of the bobbins are all carried by one or another of the sections of the outside plate of the magazine.

It is a still further object of our present invention to provide improved thread slots for the ends of the filling which extend from the bobbins held in reserve to a common thread holder, this feature of the invention including the treatment of the sides of the slots in such a way as to provide a hard high-

ly polished preferably non-metallic surface which will not abrade the filling as the bobbins pass downwardly toward transfer position.

The usual form of weft replenishing mechanism for multicolor looms includes a plurality of supports which hold a bobbin in transfer position, certain or all of said supports being yieldable at the time the transfer arm moves the bobbin into a depleted shuttle. The supports for the tip of the bobbin have ordinarily been so disposed as to engage the wooden portion of the bobbin which extends beyond the wound mass of yarn, but where bobbins of differing lengths are to be employed it is necessary to make some provision for holding the tips of the bobbins. We set forth herein two different constructions which accomplish this result, the preferred form being to space the yielding supports for the tips of the bobbins from the wooden tips of the bobbins so that they will be in contact with the cylindrical portion of the wound mass of yarn on the shorter as well as the longer bobbins. A different method may be employed by leaving the tip supports in their usual position for the shorter bobbins and winding on the long bobbin an amount of yarn which is of the same length as that on the short bobbin. This latter method limits the capacity of the replenishing mechanism so far as total reserve yarn is concerned and because of this fact we prefer to use the first named construction.

The change from one length to another of bobbins necessarily requires an alteration in the length of the corresponding cradle and to effect this change we may employ the form of bobbin release or cradle which is set forth in patent to Gordon No. 1,608,652.

With these and other objects in view which will appear as the description proceeds, our invention resides in the combination and arrangement of parts hereinafter described and set forth in the claims.

In the accompanying drawings, wherein we have shown a convenient embodiment of our invention,

Fig. 1 is a vertical section through a magazine made according to our present inven-

tion taken adjacent to the bobbin tip supporting part of the replenishing mechanism,

Fig. 2 is a front elevation taken in the direction of arrow 2, Fig. 1 and showing the bobbin support in the preferred position,

Fig. 3 is a top plan view taken in the direction of arrow 3, Fig. 2, certain parts being omitted for the sake of clearness,

Fig. 4 is a view similar to Fig. 3 but showing the modified device for supporting bobbins all of which have wound masses of yarn of the same length, and

Fig. 5 is an enlarged horizontal section taken on line 5—5 of Fig. 1 and showing the improved form of thread guide which reduces wear on the weft ends extending from the reserve bobbins to the thread holders not shown.

It is to be understood that as the bobbins await transfer they are disposed in parallel vertical stacks between two main supports, one of these supports being the inside plate which receives and guides the butts of the bobbins and the other being the outside part of the structure which guides the tips. We employ the usual method for guiding the butts of the bobbins and our present invention is related particularly to that part of the structure which lies adjacent the tip ends of the bobbins. Accordingly, we provide a weft replenishing mechanism M having a plate 10 which is provided with webs 11 the effect of which is to provide a plurality of vertical guideways for the butts of the bobbins. Supported by the bottom of said plate 10 are one or more guides 12 which may have ribs 13 defined by plates 14 or provided in any other approved manner. The support for the front of the butt of the bobbin may be similar to that shown in patent to Brouwer, No. 1,652,604, reference to which would show that a rib is employed to engage one of the rings of the bobbins to prevent endwise movement thereof away from the plate 10. If desired a rear support for the butts of the bobbins as shown in patent to Ryon No. 1,366,950 may be used. As previously stated the present invention is not related to that part of the mechanism which supports the butts of the bobbins and this portion of the replenishing mechanism may be substantially the same as that in common use and set forth in patent to Ryon No. 1,030,748. The usual tie rods 15, 16 and 17 may be employed substantially as shown in Fig. 1.

In carrying our improvements into effect we divide the outer plate for the magazine which supports the tips of the bobbins into several sections which are supported independently of each other. As shown in Figs. 3 and 4 we have provided three sections 20, 21 and 22 which correspond, respectively, to the front, central and rear stacks of the bobbins. Each of these parts is provided with openings through which extend the corre-

sponding tie rods and each part is supported by two of the tie rods as clearly shown in Fig. 1. The position of said sections longitudinally of the tie rods may be determined by means of set screws 23 and all of the tie rods will preferably be made sufficiently long so that if desired all the bobbins used may be of the longer type.

As shown herein we have illustrated our invention as permitting the use of shorter bobbins in the front cell or compartment and we have accordingly placed the section 20 nearer the plate 10 than are the remaining sections 21 and 22, so that said part 20 will cooperate with short bobbins S and the sections 21 and 22 will support the relatively longer bobbins L.

The section 20 is formed with a vertically extending slot 24 which receives the tip ends of the wooden part of the bobbins and there is mounted on the bottom portion of said section 20 the outer end of a cradle 25 the inner end of which is supported as at 26 to the plate 10. The cradle is made of two portions 27 and 28 which have a tongue and groove connection 29 as indicated in Fig. 2 and are held in adjusted position by means of screws 30. Said cradle may be substantially the same as set forth in the aforesaid patent to Gordon No. 1,608,652. The outer end of said cradle has pivotal support as at 31 with the section 20.

The central section 21 is provided with grooves or slots 31 similar in form and purpose to the slot 24 in the section 20 and in like manner the section 22 is provided with a slot or groove 32 to receive the tips of the bobbins in the rearmost stack.

In the form of the invention set forth more particularly in Fig. 3 we make use of the full capacity of the replenishing mechanism to hold reserve weft by winding each bobbin with approximately the maximum yarn which it can hold. In order to support the tips of the bobbins in transfer position we provide a pair of yielding spring supports each of which may be of the form shown in Patent No. 1,724,286 issued to King. Each of these supports includes a holder element 40 and a coil spring bobbin engaging portion 41 which is held in adjusted longitudinal and angular position in the corresponding holder by means of a bolt 42 which clamps the upper and lower holder portions 43 and 44, respectively, to hold said portions against the spring. There will be one holder and spring supported by the lower tie rod 17 at the front of the magazine and another supported by their respective tie rods by means of set the lower tie rod 15 at the rear of the magazine. Said holders are held in position on their respective tie rods by means of set screws 45 and they will be located approximately as shown in Fig. 3 so as to lie under

the cylindrical portions of the wound mass of yarn on the shorter bobbins S.

It is customary in certain weft replenishing looms to place the rear support for the tip of the bobbin at a short distance from the wooden tip as shown in patent to Chevrette No. 1,566,736, and we retain this location of the rear bobbin support, but so far as we are aware it is new to move the front support so that it also will be spaced from the wooden tip of the bobbins and will be positioned for engagement with that portion of the yarn which lies between the conical portion C of the weft and the butt of the bobbins.

15 The cradles 50 which are supported by the sections 21 and 22 may be of the usual form or may be of the type which is supported by the section 20, depending upon whether more than one compartment of the replenishing 20 mechanism is to be provided with the shorter bobbins.

In the operation of the device the weft detecting mechanism not shown will call for a change of weft when the yarn in the active 25 shuttle is substantially depleted and at this time the cradle corresponding to the active shuttle will rock on its axis to release the lowermost bobbin of the stack supported thereby, so that the bobbin may fall onto the 30 yielding supports 41. The bobbin will roll to the common transfer position indicated at T in Fig. 1, after which the transfer mechanism not shown will effect replenishment of weft. The lower portion of the central section 21 35 extends downwardly as at 60 so as to engage the tip ends of the longer bobbins L to restrain the same against longitudinal movement, but the shorter bobbins will be spaced from this portion 60 and it is for this reason 40 that we employ the ridge 13 which will be in engagement with that ring R on the butt of the bobbin which is nearest the tip thereof. By reason of the ridge the shorter bobbins will be held in proper transfer position so 45 that the rings thereof will be received by the spring clips in the shuttle. From an inspection of Fig. 3 it will be noted that the spring supports 41 will engage the cylindrical portion of the wound mass of yarn on the shorter 50 as well as the longer bobbins so that no variation in the location of the bobbins of different lengths will occur when they await transfer.

In the modified form of the invention 55 shown in Fig. 4 the wound mass of yarn is of the same length on all the bobbins and the front support 70 is moved nearer the tip than is the case in the preferred form shown in Fig. 3. In this position the support 70 will 60 engage the wooden ends of the bobbins. In this form it will be desirable to have the ridge 13 to prevent endwise movement of the shorter bobbins. By reason of the nature of the bobbins shown in Fig. 4 the short as well as 65 the long bobbins will be held in the same

correct position for transfer. In this form the rear support 71 will be located substantially the same as the rear support in the preferred form so as not to interfere with the thread extending from the conical part of the 70 yarn to the thread holder.

In both forms it will be noted that the 75 holders for the supports are movable along their respective tie rods and may be held in any longitudinal and angular position by means of the set screws 45.

Another feature of our invention relates to the construction of that portion of the sections which define the thread slots 80 shown in Fig. 1. It is understood of course that the threads which extend from the reserve bobbins must pass outwardly to a thread holder not shown and they ordinarily extend through slots similar to those shown at 80. As made heretofore, however, these slots have 80 been defined merely by slots in the cast iron of which the frame is made and it has been found that the iron surface along which the thread ends rub abrade the threads to such an extent that breakage not infrequently occurs at the time of transfer. We have found that with an ordinary weft replenishing 90 mechanism of the multicolor type a thread of a given size and strength will be worn or weakened so as to break if rubbed three times along the full length of the slot in contact with one side thereof, but it may be passed over a slot of the same length approximately thirty times without breaking if the walls of the slot are provided with enamel or similar 95 material. This feature of our invention is set forth in Fig. 5 where the cross section of the member 22 is enlarged so as to bring out more clearly the coating of enamel 85 which is applied to the rounded surface 86. Each 100 of the vertical edges of the sections 21 and 22 is provided as set forth and we find that there is a very marked reduction of the number of breakages of filling at the time of transfer which can be attributed to no other cause 105 than the use of enamel. If desired the enamel may be baked on the sections of the outside of the magazine.

From the foregoing it will be seen that we 115 have provided a magazine wherein bobbins of two different lengths may be employed at the same time and wherein the wooden tip ends of the bobbins of both lengths are substantially the same diameter. We are aware 120 of an application pending in the names of Jennings and Chevrette, wherein bobbins of two different lengths may be employed but with the tips of the bobbins of different diameters and we make no claim to such a construction. It will further be seen that the preferred form of the invention permits the use of both long and short bobbins which have wound thereon the maximum length of 125 yarn for which the bobbins are designed and that the front tip support is so placed as to 130

engage the cylindrical portion of the wound mass of yarn on the shorter as well as the longer bobbins, thus insuring proper positioning of the bobbins of both lengths as they 5 await transfer. Furthermore, it will be seen that each of the sections 20, 21 and 22 is provided with a slot or guide for the tips of the bobbins and also with means for supporting the adjacent end of the corresponding cradle 10 which cooperates with the stack of bobbins guided by the section. It is not necessary to use adjustable cradles as solid cradles of different lengths might be used. While we have shown the invention as applicable particularly 15 to the front section 20 yet the idea of the use of two lengths of bobbins set forth herein may be extended to include other sections. Again, it will be seen that by providing the slots 80 with enamel, which may be baked to 20 the cast iron base of said sections, we secure thread guides which are much superior to those heretofore used.

Having thus described our invention it will be apparent that changes and modifications 25 may be made therein by those skilled in the art without departing from the spirit and scope of the invention and we do not wish to be limited to the details herein disclosed, but what we claim is:

30 1. In weft replenishing mechanism operating with bobbins having substantially similar butts and tips and arranged in parallel stacks, the bobbins of one stack being of a length different from the length of the bobbins of another stack, means to guide the butts of the bobbins of the several stacks, guiding structure for the tips of the bobbins, said guiding structure being formed of sections which are independently movable 35 with respect to each other, one of said sections being for one stack of bobbins of a given length and another section being for a stack of bobbins of a different length, and bobbin supports to engage the yarn on the bobbins and hold the bobbins in proper 40 transfer position irrespective of the length of bobbins.

45 2. In weft replenishing mechanism operating with bobbins having substantially similar butts and tips and arranged in parallel stack, the bobbins of one stack being of a length different from the length of the bobbins of another stack, means to guide the butts of the bobbins of the several stacks, 50 guiding structure for the tips of the bobbins, rods extending from the means parallel to the axes of the bobbins in the several stacks, said guiding structure being formed of a plurality of sections supported by the tie rods, said sections being movable independently of each other along the tie rods to be at different distances from the means, one of said sections being for a stack of bobbins of a given 55 length and another of said sections being

for a stack of bobbins of a different length, and bobbin supports mounted on the rods and positioned to hold a bobbin in proper transfer position irrespective of the length of the bobbin.

3. In weft replenishing mechanism operating with bobbins having substantially similar butts and tips and arranged in parallel stacks, the bobbins of one stack being of a length different from the length of the bobbins of another stack, means to guide the butts of the bobbins of the several stacks, and guiding structure for the tips of the bobbins, said guiding structure including a plurality of separate sections, a pair of parallel rods for each section secured to and extending from the means, and means to secure each section in adjusted longitudinal position with respect to the corresponding tie rods, one of said sections being located 70 at a given distance from the first named means to cooperate with bobbins of a given length and another of said sections being at a different distance from the means to cooperate with the stack of bobbins of a different length, and bobbin supports mounted on the rods and positioned to hold a bobbin in proper transfer position irrespective of the length of the bobbin.

4. In weft replenishing mechanism operating with bobbins having substantially similar butts and tips and arranged in parallel stacks, the bobbins of one stack being of a length different from the length of the bobbins of another stack, means to guide the butts of the bobbins of the several stacks, and guiding structure for the tips of the bobbins, said guiding structure being formed of sections which are independently movable with respect to each other, one of said sections being for one stack of bobbins of a given length and another section being for a stack of bobbins of a different length, bobbin tip supports, and means to hold said supports in position to have supporting engagement with the long and short bobbins when a bobbin of either length is in transfer position.

5. In weft replenishing mechanism operating with bobbins having substantially similar butts and tips and arranged in parallel stacks, the bobbin of one stack being of a length different from the length of the bobbins of another stack, means to guide the butts of the bobbins of the several stacks, guiding structure for the tips of the bobbins, said structure being formed of sections which are independently movable with respect to each other, one of said sections being for one stack of bobbins of a given length and another section being for a stack of bobbins of a different length, and bobbin tip supports independent of the section and located to have supporting engagement with the long and short bobbins when a bobbin of 115 120 125 130

either length is in transfer position, said supports to have engagement with the cylindrical portion of the mass of yarn wound on the bobbins.

5. In weft replenishing mechanism operating with bobbins having substantially similar butts and tips and arranged in parallel stacks, the bobbins of one stack being of a length different from the length of the bobbins of another stack, means to guide the butts of the bobbins of the several stacks, guiding structure for the tips of the bobbins, said structure being formed of sections which are independently movable with respect to each other, one of said sections being for one stack of bobbins of a given length and another section being for a stack of bobbins of a different length, a bobbin releasing cradle for each section, the cradles being of 20 a length to correspond to the length of the bobbins of the associated section, and bobbin supports to receive the bobbins from the cradles, each support being positioned to hold a bobbin in proper transfer position 25 independently of the length of the bobbin.

6. In weft replenishing mechanism operating with bobbins having substantially similar butts and tips and arranged in parallel stacks, the bobbins of one stack being of a length different from the length of the bobbins of another stack, means to guide the butts of the bobbins of the several stacks, guiding structure for the tips of the bobbins, said structure being formed of sections 30 which are independently movable with respect to each other, one of said sections being for one stack of bobbins of a given length and another section being for a stack of bobbins of a different length, and a bobbin releasing cradle for each section, the cradles being of a length to correspond to the length of the bobbins guided by the associated section, each section having provision for supporting the cradle corresponding 40 to the stack of bobbins guided thereby, and bobbin supports to receive the bobbins from the cradles, each support being positioned to hold a bobbin in proper transfer position 45 independently of the length of the bobbin.

7. In a weft replenishing mechanism operating with a plurality of reserve bobbins of different lengths, means to hold the bobbins in a plurality of separate stacks, the bobbins of any one stack being of the same length, a pair of bobbin supports acting jointly to hold a bobbin in transfer position, the supports being capable of holding the bobbins from any of the stacks in proper 55 transfer position.

8. In a weft replenishing mechanism operating with a plurality of reserve bobbins of different lengths, means to hold the bobbins in a plurality of pairs of stacks, supports 60 to hold bobbins from any of the stacks in

a common transfer position, the bobbins from any stack falling on one support and moving therealong into engagement with the other support to be positioned by the latter, the bobbins of the said one pair of stacks 70 being of different lengths.

In testimony whereof we have hereunto affixed our signatures.
